INVENTOR,

Joseph W. Reid,
BY
Gardner Steeward,
ATTORNEYS

UNITED STATES PATENT OFFICE.

JOSEPH W. REID, OF PATERSON, NEW JERSEY.

ADJUSTABLE CURTAIN-POLE OR SHADE BRACKET.

SPECIFICATION forming part of Letters Patent No. 651,611, dated June 12, 1900.

Application filed March 8, 1900. Serial No. 7,783. (No model.)

To all whom it may concern:

Be it known that I, JOSEPH W. REID, a citizen of the United States, residing at Paterson, county of Passaic, and State of New Jersey, have invented certain new and useful Improvements in Adjustable Curtain-Pole or Shade Brackets; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to window-fixtures, and it has reference particularly to supporting-brackets for roller shades or curtains.

The object of the invention is to provide an inexpensive, efficient, and simply-constructed bracket of this nature the parts of which are adjustable, so as not only to accommodate curtain or shade rollers of various lengths and window-frames of various widths, but so as to be capable of sustaining each end of the roller at different elevations.

The invention consists in the improved roller-shade or curtain bracket and in the combination and arrangement of its various parts, substantially as will be hereinafter pointed out and finally embodied in the clauses of the claim.

In the accompanying drawings, Figure 1 shows a shade or curtain supported upon the frame of a window by means of my improved brackets. Fig. 2 is an enlarged view, in front elevation, of one of said brackets. Fig. 3 is a view in side elevation of said bracket, a portion thereof being broken away. Fig. 4 is a vertical sectional view of said bracket, presenting a slight modification of the invention. Fig. 5 is a view of that member of the bracket which is directly secured to the window-frame, presenting in dotted lines the modification shown in Fig. 4. Fig. 6 is a sectional view on the line xx in Fig. 5. Fig. 7 is a view in side elevation of said member of the bracket which is directly secured to the window-frame, presenting another slight modification of the invention; and Fig. 8 is a sectional view on the line yy in Fig. 7.

In said drawings, a designates a window-

frame upon which is supported by means of my improved brackets a shade or curtain b .

c designates the roller for the curtain, the same having trunnions d , which rest in the brackets.

Each bracket consists of two members, the one of which, e , is adapted to be secured to the face of the window-frame and the other of which, f , directly receives the roller-trunnion. The member e consists of a metallic plate having in its body portion an elongated horizontal slot g and provided with upwardly and downwardly extending projections h and i , respectively, the former having a hole j penetrating it and the latter being provided with a longitudinal slot k , this slot being disposed at right angles with reference to the slot g . The member f consists of a metallic plate having an integral outwardly-extending arm l projecting from its upper end. It is this arm which directly supports the trunnion of the roller, and for this purpose it may be either provided with the orifice m or the slot n (indicated in dotted lines in Fig. 3) for receiving, respectively, a round or flattened trunnion, according as the bracket is to be applied at the one or the other end of the roller. In the body portion of the member e is formed in its back surface an elongated recess o , with which the slot g communicates. In said recess fits the preferably squared head p of a bolt q , whose shank penetrates the slot g and the member f and is threaded at its free end, being adapted to receive a wing-nut r , which may be screwed thereon, so as to bind the two members tightly between the head of the bolt and said wing-nut. In order to prevent the member f from turning on the bolt when the same is slightly loosened, the body portion of said member is provided on its rear face with a horizontal rib s , which takes against the upper edge of the body portion of the member e , or said member may be provided with two ribs s on its rear face, the one taking against the upper edge and the other against the lower edge of said body portion of the other member, as shown in Fig. 4.

t is a screw which penetrates the slot k of the projection i of the member e . By manipulating this screw, which is adapted to be

driven into the woodwork of the window-frame, as shown in Fig. 1, the member *e* may be secured, as will be obvious, at various elevations on said frame. After the bracket has 5 been adjusted vertically to the proper position a screw *u* is inserted through the hole *j* and likewise driven into the window-frame to assist the screw *t* in firmly securing said bracket in position. Since the use of the 10 screw *u* will involve its being inserted as often as it becomes necessary to adjust the brackets vertically after once being put up, I have provided in the modified forms of my 15 brackets means for obviating this.

15 According to the modifications shown in Figs. 4, 5, and 6, in the back surface of the member *e* and extending upwardly from its slot *g* is formed a dovetailed groove *v*. This groove is adapted to receive the head of a 20 nail or screw *w*, which is driven into the woodwork of the window-frame before the member is secured in place by the screw *t*. By the use of this construction the member *e* of the bracket may be adjusted vertically 25 without first doing more than loosening the screw *t*.

According to the modifications shown in Figs. 7 and 8 the rear face of the member *e* is provided with a lug or projection *z*, the 30 same being adapted to project into a groove or recess *a'*, formed in the surface of the window-frame under said member.

By the use of my improved curtain or shade bracket only the simplest manipulation is 35 necessary in order to fit the shades or curtains to the window-frame when they are initially placed in position, and afterward, should one end of the roller tend to sag, as is sometimes the case when the shade is frequently operated, this may be remedied by 40 elevating the member *f* of the bracket.

Having thus fully described my invention,

what I claim as new, and desire to secure by Letters Patent, is—

1. In a window-shade bracket, the combination of two members, the one having slots extending in relatively-transverse directions, and means for adjustably connecting the two members, said means penetrating one of the two slots, and movable in the same longitudinally thereof and the means for sustaining the bracket in position being adapted to penetrate the other slot, substantially as described. 45

2. The combination, with a window-frame, of a window-shade bracket consisting of two members, the one having slots extending in relatively-transverse directions, and means for adjustably connecting the two members, said means penetrating the one of said slots 60 and movable in the same longitudinally thereof, means, penetrating the other slot, for securing said bracket to the frame, and a co-acting groove and projection engagement between said first-named member of the bracket 65 and the frame, substantially as described.

3. The combination, with a window-frame, of a window-shade bracket consisting of two adjustably-connected members of which one is the supporting member, said supporting 70 member having a dovetailed groove, means for adjustably securing said supporting member to the frame, and a headed device secured in the frame, the head of said device engaging said last-named member in the groove 75 thereof, substantially as described.

In testimony that I claim the foregoing I have hereunto set my hand this 3d day of March, 1900.

JOSEPH W. REID.
